DESIGN FOR A TIRE

Benjamin F. Grimes, Stewart, Ohio

Application July 2, 1948, Serial No. 147,356

Term of patent 14 years

(Cl. D90—20)

To all whom it may concern:

Be it known that I, Benjamin F. Grimes, a citizen of the United States of America, residing at Stewart, in the county of Athens and State of Ohio, have invented a new, original, and ornamental Design for a Tire, of which the following is a specification, reference being had to the accompanying drawing, forming a part thereof, wherein:

Figure 1 is a perspective view of a tire, showing my new design.

Figure 2 is a plan view thereof, and

Figure 3 is a transverse sectional view of the tire.

I claim:

The ornamental design for a tire, as shown.
BENJAMIN F. GRIMES.
